his ATTORNEY.

UNITED STATES PATENT OFFICE.

CHARLES W. PEELLE, OF NEW YORK, N. Y., ASSIGNOR TO RICHMOND FIREPROOF DOOR COMPANY, OF RICHMOND, INDIANA, A CORPORATION OF INDIANA.

ELEVATOR DOOR.

Application filed December 3, 1926. Serial No. 152,371.

The invention relates to elevator doors, and more particularly to vertically slideable doors of the so-called "truckable" type in which the movement of a downwardly movable door section is arrested with the top bar structure of this section in substantially the plane of the sill of a door opening, so that the top bar structure will substantially span the gap between the edge of the sill and the edge of an elevator car, and thus permit ease of movement of vehicles between the floor of a building and the elevator car.

Elevator doors of the "truckable" type are extensively used, and are essential where the width of the gap between the sill of a door opening and the edge of an elevator car is so great as to not permit the free passage of the wheels of vehicles from the sill to the car, or vice versa. The necessity for the use of doors of the truckable type is not determined by any fixed dimensions of this gap, but rather by the conditions of use of the building structure in which the doors are used.

The general practice heretofore has been to utilize the hanger bar of a door section for supporting the top bar structure of this section by engagement with stops secured to the wall angle of the guide rail structure for the door section, which construction not only affords a rigid support for this top bar structure and relieves all portions of the door below same from the stresses of loads upon this top bar, but relieves the chains or other means supporting the weight of the door in its sliding movement, and the sheaves over which these chains pass, from stresses from such loads. In other words, in truckable doors the entire weight of the door section and of loads upon the top bar thereof, are sustained by the top bar structure which forms a rigid bridge between the sill of the door opening and the platform of the elevator car, completely closing the gap at this point with the exception of narrow spaces necessary to permit the movement of the door upon the guide rail structure, and to compensate for irregularities in the wall of the shaft, and for the necessary allowance of space to permit the free movement of the elevator car.

It has been the occasional practice, heretofore, to substitute angle brackets, one arm of which is secured by bolts to the elevator door section for the stops upon the wall angle co-operating with the projecting hanger bar, but such a construction is not satisfactory

owing to the development of shearing strains upon the bolts securing these angles upon the door section which cause looseness of the angles, and in some instances, the complete separation of the angles from the door section 60 by the shearing of the bolts securing the angles in position, or the bending or breakage of such bolts.

Another practice has been to use an angle bar extending for the full width of the door 65 section exposed between the jambs of the door opening, one flange of which overhangs the sill. This overhanging flange in some instances has been cut away intermediate the jambs excepting for short distances closely 70 adjacent thereto. This construction, however, has not been extensively used, and has not given satisfactory results owing to the development of shearing stresses of the character above referred to.

In all types of truckable doors above referred to, excepting that in which the hanger bar and stops upon the wall angle are used, the transmission of loads from the door section to the wall of the elevator shaft is solely 80 by the bolts securing the angle stops in position upon the door section. The result is a lack of stability in the door structure requiring frequent repairs and heavy maintenance expense.

With the above conditions in mind, I have produced an elevator door of the truckable type, employing angle stop fittings adapted to engage the sill of a door opening, which are so embodied in the top bar structure of the 90 door section as to transmit the load of vehicles, while upon said top bar, to the wall of the elevator shaft without developing any shearing stresses upon the bolts securing said fittings in position in relation to said top bar. 95 These fittings may be made of malleable iron castings, and have dimensions which will not offer any material obstruction in the doorway. They may also be provided with strengthening webs where the greatest bending or breaking stresses occur upon the fittings, which webs will themselves offer no substantial barrier to the passage of truck wheels thereover, and not be subject to breakage from the impact of loaded trucks therewith.

The angle stop fittings are so formed as to support the weight of the door and all loads upon the top bar thereof, entirely independently of the screws, bolts or rivets for attaching the fittings to the top bar structure, these 110

bolts or rivets or other attaching means serving merely to cause the fittings to have upward and downward movement with the door section in fixed relation to the jambs of the door, and to avoid such a displacement of the fittings as would prevent the suspension of the door therefrom in the manner described. The construction of the fitting is such that it offers a reinforcement to the top and side bars of the door section adjacent the upper corners thereof, and thus contributes toward the necessary rigidity of the top bar structure.

The invention consists primarily in an elevator door embodying therein a downwardly movable panel, having a metallic top bar, the lower edge of which is presented toward the wall of the shaft and projects beyond the plane of the panel, angle metal fittings, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, and means securing said fittings in relation to said top bar, whereby disengagement of said shouldered portions of said fittings from said lower edge is prevented, and the securing means is relieved from all shearing strains resulting from the weight of the door panel and loads upon said top bar; and in such other novel features of construction and combination of parts, as are hereinafter set forth and described, and more particularly pointed out in the claims hereto appended.

Referring to the drawings,

Fig. 1 is a condensed elevation, from the floor side, of an elevator door embodying my invention;

Fig. 2 is an enlarged sectional view of the top bar structure of a door panel embodying the invention with the door in the fully opened position; and

Fig. 3 is a perspective view of one of the angle fittings.

Like letters refer to like parts throughout the several views.

In the accompanying drawings, I have illustrated the invention in connection with elevator doors of the counterbalanced type, embodying two sections oppositely movable in the same vertical plane, the upper section being indicated at A, and the lower section at B. The construction of the sections A and B, excepting as to the top bar structure of the latter and the arrangement of the running gearing therefor, is immaterial to the present invention, and will not be described, as such details are old and well known in the art.

The guide rail construction for each of the

door sections is identical with that of the other, and is also well known in the art. Such a guide rail structure ordinarily consists of a wall angle *a*, having secured thereto a guide angle *b*, with which shoes *c* mounted upon the side bars of the door sections, co-operate. This guide rail structure not only defines the opening and closing movements of the door sections, but holds both sections close to the wall of the elevator shaft, and in doors of the truckable type, prevents, or assists in preventing the tilting of the door as a result of the movement of loads thereover when the door is in the fully opened position.

The guide rail structure above referred to, ordinarily extends throughout the entire height of an elevator shaft upon opposite sides of a door opening and within the shaft.

The door sections A and B each ordinarily comprises an angle metal frame constituting the bottom and the side bars of the door section, and a part of the top bar structure thereof, one flange of this angle metal frame extending inwardly of the wall of the building, and the other flange thereof extending parallel with said wall and inwardly of the frame.

In the embodiment of the invention shown, the opening within this frame is closed by means of a metal sheathed wooden panel of the usual construction, such panels varying in thickness according to the dimensions of the door and the conditions of use. This panel in each of the sections A and B is indicated at *d*. The detailed construction of the panels, however, is immaterial to the invention, since corrugated metal or sheet iron panels may be employed if desired with changes in the top bar structure by which metal panel doors may be adapted for the heavy service required of truckable doors.

In the drawings, the angle metal frame forming a part of the top bar structure is indicated at *e*, the inwardly extending flange *e'* of this angle being located at one side of the plane of the panel *d* so that the lower edge of this top bar structure, presented toward the wall of the shaft projects beyond the plane of the panel so that this top bar may be utilized in a manner to be hereinafter described in supporting the lower door section for trucking purposes.

The other flange *e''* of the angle metal frame forming a part of the top bar structure, affords a surface onto which trucks may pass when being moved between the floor of a building and the elevator car platform.

The flange *e''* is reinforced by means of a metallic bar *f* positioned opposite to, and extending parallel with, the flange *e'*, and engaging the under face of the flange *e''*, this bar preferably extending not only from side bar to side bar of the frame, but projecting beyond said side bars to an extent to bring the flexible connections between the two sections in the

proper relation to the sheave. This construction is preferable as it adds materially to the rigidity of the top bar structure. The details of construction of the top bar structure above referred to are capable of wide variation, it being essential, however, that that portion of the top bar structure presented toward the wall of the shaft shall have the offset lower edge above referred to and indicated at *g* in the drawings. Secured to, and movable with, the top bar structure adjacent each corner thereof is an angle metal fitting having a horizontally extending flange *h* thereof projecting from said top bar structure a distance sufficient to overhang and engage the sill *C* of a door opening when the door is in the fully opened position. The lower face of this flange is on substantially the plane of the top of the top bar structure, so that the engagement of this flange with the sill *C* of the door opening will bring the upper surface of the top bar structure substantially flush with, or in the plane of, said sill. The other flange *i* of each fitting is of a depth greater than the width of the flange *e'* or its equivalent, and has formed thereon a shoulder *i'* adapted to pass under and engage the lower edge *g* throughout substantially the entire length of the fitting. One side of this flange is downwardly extended beyond this shoulder *i'* as indicated at *j*, giving the flange a general right angular arrangement laterally of the door or in the plane of the frame as well as transversely of this plane. The fitting is made of malleable iron, which may be produced with sufficient accuracy to require little or no machine work.

The flange *i* has openings *h*—*h'* through which bolts may pass to secure the fitting in contact with the flange *e'*, and an opening *h*² therethrough, through which one of the bolts as *m* securing the hanger bar *f* with relation to other parts of the top bar structure passes, and a fourth opening *h*³ by which the projection *j* may be secured to a side bar of the frame.

The form of the fitting is such as to not only sustain the load of the door and the stresses upon the top bar structure thereof, but to form an angle brace between adjacent portions of the top bar and a side bar which would have the effect of very materially strengthening this part of the door.

The rivets and bolts passing through the openings *h*—*h*³ serve merely to secure the fitting in position in relation to the frame of the door, and do not bear any part of the loads to which the door is subjected, since the engagement of the shoulder *i'* with the lower edge *g* of the flange *e'* of the top bar structure, will prevent any possible movement of the fitting which will develop a shearing action upon such bolts and rivets.

The fittings may be required at times to withstand very material stresses, and to

minimize likelihood of the breakage of these fittings at the angle between the flanges *h* and *i*, I provide reinforcing webs *h'* at this point. These webs, however, do not project more than about one-half an inch above the flange *h* so that even if, through accident, the wheels of a truck should strike same, they would offer no material obstruction to the continued movement of the truck, particularly as they are inclined as shown, and the greatest bulk of the metal is above the angle between the flanges *h* and *i*. With doors of ordinary dimensions, the panel *d* is about two inches in thickness, and the gap to be closed is in the neighborhood of four to four and one-half inches. The fitting need be no more than about six inches in length, and since it is located closely adjacent a jamb of the door opening, it would be but rarely that the wheels of a truck would strike the fitting.

The length of the fitting, however, is sufficiently great to minimize a tendency of the springing of the top bar intermediate its points of support, thus very materially assisting in securing rigidity in this top bar structure.

The flange *e*² of the top bar structure is of a width proportionate to the width of the gap between the edge of the sill and the edge of the elevator car platform, which width will vary according to official requirements as to clearance between the door and the elevator car, and between the door and the wall of the shaft, and the character of the trucking. With wide heavy doors, this gap must be proportionately wider to accommodate the door which must be of increased thickness and have much heavier metal stock in the top bar structure to withstand heavier loads. For some uses, as in garages, the angle fittings may be located not only adjacent the jambs, but at points intermediate the jambs, and thus minimize any tendency of the top bar structure to sag under a load. With narrower doors the angle fittings are required only adjacent the jamb. Where ordinary hand trucks are used, the clearance between the edge of the flange *e*² and the elevator car may be from an inch to an inch and three-quarters, but with vehicles having smaller wheels, it will be necessary to shorten this clearance.

In either large or small doors, however, not only the load of the door itself but of vehicles upon the top bar structure thereof will be transmitted directly to the wall of a shaft below the sill by the angle fittings *e*, the engaging relation of the shoulder *i'* with the edge *g* causing a direct transmission of such loads from the top bar *e* to the fittings, none of this load coming upon the rivets or bolts used in securing the fittings to the top bar structure. These bolts or rivets serve merely to maintain the necessary engagement of the shoulder *i'* with the projecting edge *g* of the top bar structure.

Since the shoes *c* straddle the guide rail *b* and have merely a free running fit therewith, it is apparent that any tilting of the door section toward or from the wall of the elevator shaft, with the movement of a load upon said top bar structure, will be prevented by these shoes and guide rails.

By making the fittings of malleable iron, I not only am enabled to economically produce such fittings, but secure a high degree of strength of material adjacent the angle between the flanges *h* and *i* where such strength is required to secure durability.

In the accompanying drawings, I have illustrated the invention in connection with counterbalanced elevator doors having an upper and a lower section, but it is obvious that a single, downwardly movable section could be used without any changes in the top bar structure and the angle fittings so far as the construction and arrangement of parts is concerned. Ordinarily, however, doors of the counterbalanced type are used.

I also prefer to utilize the angle fittings as corner braces at opposite ends of the top bar structure, as such contribute toward the required strength and rigidity of the door adjacent the top bar. By passing the bolt *m* completely through the door and through the hanger bar, I am enabled to more effectively incorporate the angle fittings in the top bar structure.

It is not my intention to limit the invention to the precise details of construction shown in the drawings, since it is apparent that such may be varied when adapting the invention to different constructions and designs of doors, without departing from the spirit and scope of the invention.

Having described the invention, what I claim as new and desire to have protected by Letters Patent, is:—

1. An elevator door embodying therein a downwardly movable panel, having a metallic top bar, the lower edge of which is presented toward the wall of the shaft and projects beyond the plane of the panel, angle metal fittings, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, and means securing said fittings in relation to said top bar, whereby disengagement of said shouldered portions of said fittings from said lower edge is prevented, and the securing means is relieved from all shearing strains resulting from the weight of the door panel and loads upon said top bar.

2. An elevator door embodying therein a downwardly movable panel, having a metal-

lic top bar, the lower edge of which is presented toward the wall of the shaft and projects beyond the plane of the panel, and metallic side bars, angle metal fittings, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, said last named flange having an extension adapted to engage a side bar, and means securing said shouldered flanges with relation to said top bar, whereby disengagement of said shouldered portions of said fittings from said lower edge is prevented, and the securing means is relieved from all shearing strains resulting from the weight of the door panel and loads upon said top bar, and means securing said extension to said side bar whereby each fitting is caused to act as a corner brace between the top bar structure and the side bars of the panel.

3. An elevator door embodying therein a downwardly movable panel, having a metallic top bar, the lower edge of which is presented toward the wall of the shaft and projects beyond the plane of the panel, angle fittings of malleable cast metal, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, reinforcing webs adjacent the angle between the flanges of each of said fittings, and means securing said fittings in relation to said top bar, whereby disengagement of said shouldered portions of said fittings from said lower edge is prevented, and the securing means is relieved from all shearing strains resulting from the weight of the door panel and loads upon said top bar.

4. An elevator door embodying therein a downwardly movable panel, having a metallic top bar, the lower edge of which is presented toward the wall of the shaft and projects beyond the plane of the panel, and metallic side bars, angle fittings of malleable cast metal, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, said last named flange having an extension

adapted to engage a side bar, reinforcing webs adjacent the angle between the flanges of each of said fittings, means securing said shouldered flanges with relation to said top bar, whereby disengagement of said shouldered portions of said fittings from said lower edge is prevented, and the securing means is relieved from all shearing strains resulting from the weight of the door panel and loads upon said top bar, and means securing said extensions to said side bars whereby each fitting is caused to act as a corner brace between the top bar structure and a side bar of the panel.

5. In an elevator door, the combination with guide rail structures upon opposite sides of a door opening within an elevator shaft, of a downwardly movable panel having an angle metal frame constituting top, bottom and side bars, shoes upon said side bars straddling the guide rails upon opposite sides of a door opening whereby tilting of a door toward or from the wall of a shaft is prevented, a panel closing the opening in said frame, the lower edge of the top bar of said frame being presented 20 toward the wall of the shaft and projecting beyond the plane of said panel, angle metal fittings, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, and means securing said fittings in relation to said top bar, whereby disengagement of said shouldered portions of said fittings from said lower edge is prevented, and the securing 30 means is relieved from all shearing strains resulting from the weight of the door panel and loads upon said top bar.

6. In an elevator door, the combination with guide rail structures upon opposite sides of a door opening within an elevator shaft, of a downwardly movable panel having an angle metal frame constituting top, bottom and side bars, shoes upon said side bars straddling the guide rails upon opposite sides of a door opening whereby tilting of a door toward or from the wall of a shaft is prevented, a panel closing the opening in said frame, the lower edge of the top bar of said frame being presented toward the wall of the shaft and projecting beyond the plane of said panel, angle fittings of malleable cast metal, one flange of each of which projects from said top bar to a position where, when the section is lowered, it will engage the sill of a door opening, and stop the top bar with its upper surface maintained substantially flush with

the sill of a door opening, and the other flange of each of which is provided with a shouldered offset portion passing under and engaging the said lower edge of the top bar, 65 said last named flange having an extension adapted to engage a side bar, reinforcing webs adjacent the angle between the flanges of each of said fittings, means securing said shouldered flanges with relation to said top bar, whereby disengagement of said shouldered portions of said fittings from said lower edge is prevented, and the securing means is relieved from all shearing strains 70 resulting from the weight of the door panel and loads upon said top bar, and means securing said extensions to said side bars whereby each fitting is caused to act as a corner brace between the top bar structure and a side bar of the panel.

7. In an elevator door, the combination with guide rail structures upon opposite sides of a door opening within an elevator shaft, of a downwardly movable panel having an angle metal frame constituting top, bottom and side bars, shoes upon said side bars straddling the guide rails upon opposite sides of a door opening whereby tilting of a door toward or from the wall of a shaft is prevented, a panel closing the opening in said frame, a hanger bar upon the side of said panel opposite said frame, means securing said hanger bar to said frame, an upwardly movable panel operatively connected with said downwardly movable panel, the lower edge of the top bar of said frame being presented toward the wall of the shaft and projecting beyond the plane of said panel, angle fittings of malleable cast metal, one flange of each of which projects from said top bar to a position where, when the section is lowered, it will engage the sill of a door opening, and stop the top bar with its upper surface maintained substantially flush with the sill of a door opening, and the other flange of each of which is provided with a shouldered offset portion passing under and engaging the said lower edge of the top bar, and means securing said shouldered flanges with relation to said top bar, including a bolt passing 105 through said flange, said top bar, said panel and said hanger bar, whereby disengagement of said shouldered portions of said fittings from said lower edge is prevented, and the securing means is relieved from all shearing strains resulting from the weight of the door panel and loads upon said top bar.

In witness whereof I have hereunto affixed my signature, this 20th day of November, 1926.

CHARLES W. PEELLE.
